[57] **CLAIM**

The ornamental design for a lightning detector and advance storm warning instrument, as shown and described.

DESCRIPTION

FIG. 1 is a top perspective view of a lighting detector and advanced storm warning instrument showing my new design;

FIG. 2 is a top perspective view thereof, with the lid shown in open condition;

FIG. 3 is a left side elevational view thereof, with the right side being a mirror image;

FIG. 4 is a top plan view thereof;

FIG. 5 is a rear elevational view thereof;

FIG. 6 is a left side elevational view thereof, with the lid shown in closed condition;

FIG. 7 is a top plan view thereof;

FIG. 8 is a bottom plan view thereof;

FIG. 9 is a front elevational view thereof; and

FIG. 10 is a right side elevational view thereof.

FIG. 1

FIG. 2
